UNITED STATES PATENT OFFICE.

FRANK G. WHEELER, OF APPLETON, WISCONSIN, ASSIGNOR TO BLEACH PROCESS COMPANY, OF APPLETON, WISCONSIN, A CORPORATION OF WISCONSIN.

INDICATING DEVICE FOR ELECTROLYTIC CELLS.

1,312,494.

Specification of Letters Patent.

Patented Aug. 5, 1919.

Application filed May 22, 1916. Serial No. 99,093.

To all whom it may concern:

Be it known that I, FRANK G. WHEELER, a citizen of the United States, residing at Appleton, in the county of Outagamie and 5 State of Wisconsin, have invented certain new and useful Improvements in Indicating Devices for Electrolytic Cells, of which the following is a specification.

This invention relates to level indicators 10 for electrolytic cells, such for example as cells used for the electrolysis of brine, the object of the invention being to provide a very simple and effective indicating device which is not liable to derangement from me- 15 chanical or other causes. The indicator is chiefly used in connection with the individual cells of a series-connected circuit.

My indicating device depends for its operation upon the fact that the potential of the 20 electrolyte in either compartment of an electrolytic cell is the same as that of the electrode with which it is in contact, the potential of the anolyte for example being the same as that of the anode. I provide a relatively 25 high resistance circuit in shunt between the anode electrolyte (anolyte) and the cathode, inserting in said circuit a lamp or other indicating device or mechanism having a resistance and voltage adaptable to 30 that of the individual cell. The contact with the electrolyte is established at the level which it is desired to maintain, with the result that in case the level of the electrolyte falls below this point the circuit is inter- 35 rupted and the lamp extinguished. By the use of this device a large number of cells can be controlled by a single operator, who, in case a lamp is extinguished, will introduce the brine or other electrolyte into the cell 40 in question or adjust the feed thereof to re-establish and maintain the circuit through the lamp.

One simple illustrative embodiment of the invention is shown in the accompanying 45 drawing, wherein Figure 1 is a vertical section of a portion of an electrolytic cell having my device applied thereto; and Fig. 2 is a diagrammatic illustration of a series of cells, of the kind shown in my Patent No. 50 1,236,025 patented Aug. 7, 1917.

In Fig. 1, the numeral 1 indicates the anode, 2 the cathode, and 3 the diaphragm of an electrolytic cell, the precise type or character of which is not material to the present 55 invention. The cell shown is of the type de-

scribed in my Patent No. 1,236,025, patented August 7, 1917, above referred to. 4 represents the external cell-casing. 5 is a rod which may be of carbon, graphite, platinum or any other material unaffected by the electrolyte, this rod being preferably vertically adjustable and so positioned that its lower end contacts properly with the anolyte at the normal working level 6. At its upper end the rod 5 contacts with one terminal of a 65 low-voltage electric lamp 7, the other terminal of which is connected by a lead 8 to the cathode 2.

As will be readily understood the lamp, the voltage of which corresponds substantially to the normal operating voltage of a single cell, will remain lighted so long as the electrolyte does not fall materially below the predetermined level; and its extinguishment or even dimming through imperfect contact 70 between the rod 5 and the electrolyte, affords an instant indication with respect to a drop in level of the electrolyte. Furthermore, the lamp is serviceable to some degree as an indication of the voltage of each particular 75 cell, inasmuch as it tends always to burn more brightly with increasing potential difference across the cell.

My invention is not limited to the use of a lamp as an indicator in the relation above 80 described, since it will be obvious to those skilled in the art that other indicating devices might be employed; as for example a bell included in a relay circuit and arranged to ring in case of interruption of the direct 85 circuit by a fall in level of the electrolyte. Such an arrangement is shown at the left hand of Fig. 2, in which the circuit between the electrodes 2 and 5 includes a relay magnet 10, whose armature is normally held 90 against stop 12. Should the level of the electrolyte fall unduly, the magnet is deenergized and the armature is retracted by spring 13 against stop 14, thereby closing a local 95 circuit including a battery 15 and bell 16. The lamp is however preferred as affording 100 the most positive and direct indication of the conditions within the cell.

Obviously, the shunt connection may extend between the anode and the catholyte 105 in case an indication of the level of the latter is desired.

I claim:

1. In an electrolytic cell, the combination with the anode, cathode and electrolyte, of 110

an additional electrode extending to the normal level of the electrolyte, a shunt circuit including one electrode, the electrolyte and the additional electrode, and a device in said shunt circuit for indicating an interruption thereof.

2. In a series-connected group of electrolytic cells, the combination with the anode, cathode and electrolyte of an individual cell, of an additional electrode extending to the normal level of the electrolyte, a shunt circuit extending between one electrode and the electrolyte in contact with an electrode of opposite polarity, and a device in said shunt circuit for indicating an interruption thereof.

3. In an electrolytic cell, the combination with the anode, cathode and electrolyte, of an additional electrode extending to the normal level of the electrolyte, a shunt circuit including one electrode, the electrolyte and the additional electrode, and a lamp in said circuit operating at a voltage corresponding to the potential difference between the electrodes.

4. In a series-connected group of electrolytic cells, the combination with the anode, cathode and electrolyte of an individual cell, of an additional electrode extending to the normal level of the electrolyte, a shunt circuit extending between one electrode and the electrolyte in contact with an electrode of opposite polarity, and a lamp in said circuit operating at a voltage corresponding to the potential difference between the electrodes.

5. In a contents indicator, a receptacle, an electrolytic fluid characterized by conductivity, a positive element, a negative element, and an electrode projecting below the

level of the fluid and adapted to constitute another element when said fluid is in contact therewith, an energized circuit between said electrode and one of said other elements, and an indicator in said circuit, whereby the presence of an abnormal condition in the system will be indicated.

6. In a contents indicator, a receptacle having positive and negative electrodes, and an electrolytic solution constituting an energizing means, another electrode coöperating with one of said first-mentioned electrodes and with the solution constituting energizing means and projecting below the level of the solution such a distance that when the level lowers sufficiently the electrical connection between the last mentioned electrodes will be broken, and conductive means connecting said last-mentioned electrodes and normally forming with said solution a circuit.

7. In a contents indicator, a receptacle, a fluid characterized by conductivity, a positive element, a negative element, and an electrode of a character opposite to one of the elements and adapted to constitute another element when said fluid is in contact therewith, an energized circuit between said electrode and one only of the said other elements, and an indicator in said circuit, whereby the presence of an abnormal condition in the system will be indicated.

In testimony whereof I affix my signature in presence of two witnesses.

FRANK G. WHEELER.
